Letters Patent (Design No. 63) dated 25th July 1846
antedated March 29th 1846

The Schedule referred to in these Letters Patent and
making part of the same.

To all whom it may concern:

Be it known that I, Samuel D. Vose, of Albany in the County of Albany and State of New York, have invented or produced a new Design for an Ornamental Parlor Stove; and I do hereby declare that the following is a full, clear and exact description thereof, reference being had to the accompanying drawings, making part of this Specification in which Fig. 1 is a perspective view of a stove after my design, and Figs. 2, 3, 4, 5, & 6, drawings of the different plates upon a larger scale to show the detail of ornament.

The ornaments consist of scrolls, foliage &c. not easily described.

in words, but fully represented in the drawings - The upper portion is in the style of Louis XIV and all the figures are placed upon a base ground. The different plates are lettered to show their position in the stove, corresponding letters being placed upon the various plates of Fig. 1. Thus e (Fig. 6 & 1,) will be seen to be the end door, &c.

The portions of plates left blank in the drawings are similar to and symmetrical with, the adjoining portions.

What I claim as my invention and desire to secure by Letters Patent, is the combination and arrangement of ornamental figures herein shown and described, forming a design for an ornamental Parlor Stove.
